UNITED STATES PATENT OFFICE.

MARCOS SINGER, OF YONKERS, NEW YORK.

VERNIER DIAL.

Application filed December 20, 1924. Serial No. 757,110.

To all whom it may concern:

Be it known that I, MARCOS SINGER, a citizen of the United States, and resident of Yonkers, Westchester County, State of New York, have invented certain new and useful Improvements in Vernier Dials, of which the following is a specification.

This invention relates to an improved vernier dial, which is particularly designed for use in connection with radio apparatus, whereby a fine adjustment or "tuning" may be obtained for the resistance or induction coils, or for the condenser plates.

It is the primary object and purpose of my present improvements to provide a vernier for a condenser, variocoupler or variometer of a radio receiving apparatus, which is so constructed that the necessary adjustments may be easily and quickly made to repeatedly bring or "tune" in a desired station, at the same dial reading, and which permits of the use of the device in connection with radio apparatus of the numerous makes now in general use, without involving material structural alterations thereof.

It is a further general object of the invention to provide a radio vernier, the several parts of which are of exceedingly simple construction so that the device may be manufactured and sold at a comparatively low cost.

With the above and other objects in view, the invention consists in the improved vernier and in the form, construction and relative arrangement of its several parts as will be hereinafter more fully described, illustrated in the accompanying drawings and subsequently incorporated in the subjoined claims.

40 In the drawings, wherein I have illustrated one simple and practical embodiment of the invention, and in which similar reference characters designate corresponding parts throughout the several views,—

45 Figure 1 is an elevation showing my improved vernier dial as applied to the insulating panel and coupler or condenser shaft of a radio apparatus,

50 Figure 2 is a vertical sectional view taken on the line 2—2 of Figure 1,

Figure 3 is a detail elevation of the dial arm,

Figure 4 is a detail view of one of the parts, and

55 Figures 5 and 6 are detail views illustrating the vernier adjustment means.

Referring in detail to the drawings, 5 designates the front panel of the cabinet or case for the radio apparatus, through which the shaft 6 of the variocoupler, variometer or condenser, as the case may be, extends. This shaft end is secured in a bushing 7, which is rotatably mounted in said panel, by means of the set screw 8, said bushing being fitted through an opening provided in a dial plate 9, which is suitably fixed to the face of the panel 5, as by one or more screws indicated at 10.

The dial plate is of substantially semi-circular form and the curved perimeter thereof is outwardly flanged or off-set from the face of the panel 5 as shown at 11. The surface of this off-set flange is calibrated, as shown at 12.

To the outer end of the bushing 7, the lower end of an arm 13 is fixed, said arm being spaced from the dial plate 9 and parallel therewith, and extending beyond the calibrated flange 11. The end of said arm is inwardly and downwardly bent around the edge of the flange 11 and extends between said flange and the face of the panel 5, as shown at 14, thereby providing a guide for said arm and preventing its displacement out of alignment with the dial. The arm 13 is provided with a longitudinally extending slot 15 for a purpose which will be presently explained, and at the outer end of said slot, said arm is provided with an inwardly projecting index spur 16, for movement over the calibrations 12 on the dial flange 11. A slide member 17 is longitudinally movable in the slot 15 and is provided with an opening therethrough in which a shaft 18 is loosely engaged. The slide 17 is formed on one end with a flange 19 engaging upon the inner face of the arm 13. Upon the outer end of the shaft 18 an operating knob 20 of suitable form is secured as by means of the set screw 21 and the inner end of said shaft is formed with an eccentric end portion 22. Between this eccentric end portion of said shaft and the flange 19 of the slide 17, a leaf spring 23 is interposed and normally acts to hold the shaft 18 against outward axial movement and retain said eccentric end 22 of said shaft in any one of the spaced radially extending series of openings 24, which are formed in the dial plate 9 in alignment with spaced calibrations 12.

The knob 20 at its inner end is also pro-

vided with a vernier dial 25 which has a curvilinear edge extending through substantially 90° , and provided upon its outer face with the relatively fine calibrations indicated at 26. These calibrations are adapted to be read in conjunction with a longitudinally extending index line 27 on the face of the arm 13, said line being bi-sected by the curve spaced lines 28, the spacing of these lines corresponding with the radial spacing of the openings 24 in the dial plate 9.

In the operation of the device above described, the general adjustment is first made by pulling outwardly on the knob 20 to release the eccentric end 22 of the shaft 18 from connection with the dial plate 9, and then shifting the arm 13 over the face of the dial plate, in which movement of said arm, the shaft 6 is of course rotated. When the index spur 16 of the arm registers with the desired calibration 12 in line with one of the series of openings 24, the knob 20 is released so that the spring 23 acts to engage the eccentric end 22 of the shaft in one of the openings 24. A further rotation of the shaft 6 and a finer adjustment is then obtained by rotating the knob 20, until one of the calibrations on the plate 25 registers with the index line 27 on the arm 13. In this rotation of the shaft 18, it will be apparent that owing to the engagement of its eccentric end 22 in the opening of the fixed dial plate 9, a further movement is imparted to the arm 13 which likewise causes a further rotation of the shaft 6 to the extent determined by the movement of the dial plate 25. The extent of such rotation of the shaft 6 for the purpose of securing a finer adjustment, in proportion to the movement of the dial plate 25 may be varied by shifting the shaft 18 and said dial plate longitudinally along the arm 13 so as to engage the eccentric end of said shaft in a selected opening 24 at a predetermined distance from the shaft center. In this longitudinal adjustment of the dial plate upon the arm, the registration of the curved edge of said plate with one of the horizontal lines 28 extending across the index line 27, determines when the eccentric end of the shaft 18 is in proper position to register with the opening 24. In this manner, it will be evident that a very fine vernier or micrometer adjustment of the condenser, variometer or variocoupler, as the case may be, may be very quickly secured. In practice, I propose to form the dial plate 9 from such materials, or to provide said plate with a surface of such character that it may be written upon. Thus, the user can note beside the proper opening 24, the reading on the vernier dial plate 25, in conjunction with the symbols of the sending or broadcasting stations, which is in "tune" with the receiving apparatus at that

particular adjustment, and thereafter he can, at any time, "tune" in the same station by adjusting the dial to the indicated position.

While I have in the accompanying drawings, indicated a certain number of the radial lines or openings 24, and a certain spacing of the same in a dial plate, it will be understood that the number of such openings may be decreased or increased, as may be found desirable, and the area of the vernier dial plate 25 and the number of calibrations thereon can likewise be varied to secure any desired fineness in the adjustment thereof.

From the foregoing description, considered in connection with the accompanying drawings, the construction and manner of operation of my improved vernier dial will be clearly and fully understood. The several parts as herein described may be easily produced at a nominal cost so that the device, as a whole, can be inexpensively manufactured.

It will also be noted that the use of my improved vernier dial involves no alterations of a material character in radio apparatus, to which it may be applied, and that such application can be readily made to existing radio receiving apparatus by the individual owner without requiring the services of a skilled radio mechanic. Although I have herein referred to a construction and arrangement of the several parts of my invention, which I believe to be quite desirable, it will nevertheless be understood that the device is susceptible of construction in various other alternative embodiments and I therefore reserve the privilege of resorting to all such legitimate changes in the detail features thereof as may be fairly embodied within the spirit and scope of the invention as claimed.

I claim:

1. In a vernier dial, a main dial plate having a calibrated surface, an arm connected at one end to the part to be adjusted and having an index at its other end movable over the calibrated surface of said dial, a vernier dial, means for mounting said vernier dial for longitudinal adjustment on said arm, said means including a shaft in fixed relation to said vernier dial and adapted to be rotated to adjust said dial with respect to an index on said arm, means yieldingly urging said shaft axially into engagement with the main dial plate, and said dial plate and shaft having means to coact in any one of the adjusted positions of said vernier dial, whereby, upon rotation of the latter dial with respect to the index on said arm, a further adjustment of said arm with respect to the main dial plate is obtained.

2. In a vernier dial, a main dial plate

having a calibrated surface, an arm connected at one end to the part to be adjusted and having an index at its other end movable over the calibrated surface of said dial, a vernier dial, means for mounting said vernier dial for longitudinal adjustment on said arm, said means including a shaft in fixed relation to said vernier dial and adapted to be rotated to adjust said dial with respect to an index on said arm, means yieldingly urging said shaft axially into engagement with the main dial plate, said main dial plate having a plurality of series of radially extending spaced openings, and said shaft being provided with an eccentric end portion adapted for engagement in a selected opening in one of the adjusted positions of the vernier dial, whereby, upon rotation of the latter dial, a further adjustment of said arm with respect to the first named dial plate is obtained.

3. In a vernier dial, a main dial plate adapted to be fixed to a panel and provided with an off-set flange having calibrations thereon, an arm fixed at one of its ends to a part to be adjusted and having its other end slidably engaged with said flange and provided with an index spur moving over the calibrations thereon, a vernier dial plate adjustable longitudinally along said arm and rotatable with respect thereto, and means for imparting a further adjustment to said arm upon said first named dial in the rotation of said vernier dial plate.

4. In a vernier dial, a main dial plate adapted to be fixed to a panel and having an off-set calibrated flange, an arm fixed at one of its ends to a shaft rotatably mounted on said panel and slidably engaged at its other end with said calibrated flange for movement thereover in the initial adjustment of said shaft, a rotatable vernier dial plate carried by said arm, and means fixed for rotation with said vernier dial plate and coacting with means on said first named dial plate to impart a further movement to the arm over the latter dial plate and obtain a finer adjustment of said shaft.

5. In a vernier dial, a main dial plate adapted to be secured to a panel, and hav-

ing an off-set calibrated flange, an arm adapted to be fixed at one of its ends to a shaft mounted in said panel, the other end of said arm extending around said flange and guided thereby, said arm having an index for movement over the calibrations of said flange, a shaft and means for mounting said shaft on said arm for longitudinal and rotative movement, a vernier dial fixed on said shaft, said arm having an index line with respect to which the calibrations on said latter dial are adapted to be positioned, and said first named dial plate and said shaft having means to coact in any one of the adjusted positions of said vernier dial to impart a further movement of said arm in the rotation of said shaft and obtain a finer adjustment of said first named shaft.

6. In a vernier dial, a main dial plate adapted to be secured to a panel, and having an off-set calibrated flange, an arm adapted to be fixed at one of its ends to a shaft mounted in said panel, the other end of said arm extending around said flange and guided thereby, said arm having an index for movement over the calibrations of said flange, a shaft and means for mounting said shaft on said arm for longitudinal and rotative movement, a vernier dial fixed on said shaft, said arm having an index line with respect to which the calibrations on said latter dial are adapted to be positioned, said first named dial plate having a plurality of radially extending series of openings therein and said latter shaft having an eccentrically off-set portion to engage in said openings, and a spring yieldingly urging said shaft axially towards the first named dial plate, said eccentric shaft portion coacting with said dial plate in any adjusted position of said vernier dial to impart a further movement to said arm in the rotation of said shaft and thereby obtain a finer adjustment of the first named dial.

In testimony that I claim the foregoing as my invention, I have signed my name hereto.

MARCOS SINGER.
